UNITED STATES PATENT OFFICE.

THOMAS K. BENTON, OF GLENRIDGE, NEW JERSEY.

DESIGN FOR A BACK FOR BRUSHES OR SIMILAR TOILET ARTICLES.

SPECIFICATION forming part of Design No. 36,476, dated August 4, 1903.

Application filed July 11, 1903. Serial No. 165,190. Term of patent 3½ years.

To all whom it may concern:

Be it known that I, THOMAS K. BENTON, a citizen of the United States, residing at Glenridge, in the county of Essex and State of New Jersey, have invented a new, original, and ornamental Design for a Back for Brushes or Similar Toilet Articles; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The single figure of the drawing is a plan of the back of a brush, mirror, or similar toilet article and is deemed sufficient to clearly illustrate the design.

What I claim as new is—

The ornamental design for a back for brushes and similar toilet articles as shown.

In testimony that I claim the foregoing I have hereunto set my hand this 6th day of July, 1903.

THOMAS K. BENTON.
